UNITED STATES PATENT OFFICE.

EMILE GEVERS-ORBAN, OF MONTEGNÉE, NEAR LIÈGE, BELGIUM.

PROCESS OF PRESENTING THE HYDROCARBON IN THE FORM OF A THIN FILM OF LARGE SURFACE AREA TO THE ACTION OF AN OXIDIZING AGENT.

1,404,435.

Specification of Letters Patent. Patented Jan. 24, 1922.

Application filed December 26, 1912. Serial No. 738,713.

(GRANTED UNDER THE PROVISIONS OF THE ACT OF MARCH 3, 1921, 41 STAT. L., 1313.)

To all whom it may concern:

Be it known that I, EMILE GEVERS-ORBAN, engineer, a subject of the King of the Belgians, and resident of Montegnée, near 5 Liège, Belgium, have invented a certain new and useful Process of Presenting the Hydrocarbon in the Form of a Thin Film of Large Surface Area to the Action of an Oxidizing Agent, of which the following is a specification.

It is well known that hydrocarbons such as Mazout or tar become by oxidation thicker or more bituminous.

Various methods and apparatus have been 15 suggested or adopted for oxidizing these hydrocarbons by means of air, ozone or chemicals.

Most frequently such a process has for its 20 object the manufacture of pitch or of bitumen and requires either the simultaneous or subsequent distillation of the lighter not oxidized products.

The process which forms the subject of my 25 invention, accomplishes both the oxidation and the distillation, or more exactly evaporation, in one operation and in a new manner, by the use of large surfaces provided for the purpose of presenting the hydrocarbon in the form of a thin film of large 30 surface area to the action of an oxidizing agent. These surfaces are covered with thin, continually renewed pellicles of hydrocarbon, while the surfaces are slowly moving through a current of air.

The surfaces provided for the purpose 35 of convection, passing continuously through the liquid, are working at the same time somewhat as agitators, which greatly enhances the heating and evaporating.

The surfaces, by passing through a current of air, owing to their comparatively 40 large area, produce a strong oxidation of the liquid adhering to them, and produce also a strong evaporation of the lighter products.

By virtue of this manner of presenting 45 the hydrocarbon to the oxidizing agent, the hydrocarbon may be simultaneously submitted to three different operations, viz:—stirring, oxidation, and evaporation, and the 50 oxidizing and evaporating processes may be carried on in the most efficient manner.

Somewhat similar processes of oxidation

have been employed in cleaning vegetable oils. In such processes, however, as the result sought is different, the oil is stirred 55 rather for the purpose of mechanically separating the oil from other liquids than for the purpose of presenting the oil to oxidizing agents.

Still other similar processes are known 60 for presenting liquid hydrocarbon to the action of an oxidizing agent. These processes, as far as is known to the applicant, have the disadvantage that the liquid hydrocarbons are agitated to such an extent that 65 there is a tendency for the light and heavy products to be distilled together and not perfectly separated.

On the other hand, in my process, owing 70 to the large extent of the surfaces of the hydrocarbons presented to the action of the air, and owing to their slow movement, I realize the chemical reaction, as well as the separation of the lighter products, to be 75 evaporated, from the heavy products, to be oxidized, in a rapid and efficient manner.

As the separation of the light products 80 for distillation is more easily effected in my process, these products are purer, less numerous, and leave behind them a much higher percentage of bituminous products.

The process is illustrated by a drawing, annexed hereto, in which:

Fig. 1 is a sectional side elevation of 85 the apparatus.

Fig. 2 is a larger vertical section of the apparatus.

A heated tank or boiler containing the liquid hydrocarbon.

The surfaces provided for the purpose 90 of convection 3, made of iron plates, are fixed on a revolving shaft 4 driven by the pulley 5. A current of air enters through the inlet 6. The outlet for both, air and gas, towards the serpentine is indicated by 95 7.

This plant is evidently much cheaper than that required for the purpose which consists of blowing air through the liquid mass, whereto an air compressor and high or deep tanks are required.

The arrangement can of course be varied as to constructive details. The plates which are adapted to present the hydrocarbons in the form of films may of course be of vari-

ous shapes. The air may be either hot or cold, and may be passed through the tank in any well-known manner.

The heating may be accomplished by fire 5 or by steam, or by heating internally the iron plates for convection purposes.

The process may be made continuous by causing the hydrocarbon to enter in at one end of the boiler or tank and to leave from 10 the other end. Various combinations of plates or barriers may be arranged for causing the liquid to move in a methodical way with respect to the air.

This process can be combined with any 15 other process of previous or subsequent oxidation produced in any other apparatus.

This process may also be used for oxidation of any oily or viscous liquid.

What I claim and desire to secure by Letters Patent of the United States is:

1. A process of treating hydrocarbons which consists in presenting the hydrocarbons in the form of thin films of large area to the action of an oxidizing and evaporating medium and slowly moving such films in such medium.

2. A process of treating hydrocarbons which consists of heating the hydrocarbons and simultaneously evaporating the lighter 30 constituents thereof and oxidizing the heavier constituents thereof by submitting slowly moving thin films thereof of large area to an oxidizing and evaporating medium.

3. A process of enriching hydrocarbons in bituminous constituents which consists of

heating the hydrocarbons, gently stirring and presenting thin films thereof on carriers to a current of air or other gas, the movement of such carriers being slow to allow 40 the lighter constituents of the hydrocarbons to be evaporated and the heavier constituents thereof oxidized.

4. A process of treating hydrocarbons which consists of heating the hydrocarbons, 45 simultaneously evaporating the lighter constituents thereof and oxidizing the heavier constituents thereof by submitting slowly moving thin films thereof of large area to an oxidizing and evaporating medium and 50 constantly renewing the supply of hydrocarbons, presenting fresh films thereof to the action of said medium and drawing off the hydrocarbon which has been acted upon.

5. A process of continuously treating 55 hydrocarbons which consists of heating the hydrocarbons in a containing vessel, simultaneously evaporating the lighter constituents thereof and oxidizing the heavier constituents thereof by submitting slowly moving thin films thereof of large area to an oxidizing and evaporating medium and 60 moving the body of the hydrocarbons and said medium in opposite directions with respect to each other in the containing vessel.

In witness whereof I have hereunto set my hand in the presence of two witnesses.

EMILE GEVERS-ORBAN.
